UNITED STATES PATENT OFFICE.

JOHN W. HERRICK, OF MILWAUKEE, WISCONSIN, ASSIGNOR TO THE FULLER-WARREN COMPANY, OF SAME PLACE.

DESIGN FOR A HEATING-STOVE.

SPECIFICATION forming part of Design No. 26,248, dated November 3, 1896.

Application filed July 8, 1892. Serial No. 439,420. Term of patent 7 years.

To all whom it may concern:

Be it known that I, JOHN W. HERRICK, of Milwaukee, in the county of Milwaukee and State of Wisconsin, have invented and produced a new and original Design for Heating-Stoves; and I do hereby declare that the following is a full, clear, and exact description of the invention, which will enable others skilled in the art to which it pertains to make and use the same, reference being had to the accompanying drawing, and to the letters of reference marked thereon, which form a part of this specification.

My design relates to the ornamental form, contour, and surface ornamentation of heating-stoves, the leading characteristic features of which are a central vertical column in front separating the mica-sections of the body into two parts or panels, the contour and ornamentation of the body, and the shape and ornamentation of the base, besides certain minor features hereinafter particularly described, and pointed out in the claim.

The accompanying drawing is a perspective view of a stove embodying my design.

A indicates the top of the stove, annular in general form and rounded vertically toward its outer edge, which is surrounded by a plain band 1, and ornamented inside of and above said band with scrollwork 2 in low relief. Around its inner edge it is provided with a transversely-fluted ovolو molding 3.

B is a dome-shaped cover mounted upon the top A and having a plain band 4 around the base and scrollwork ornamentation 5 above said band. The cover is surmounted by an ornament C, consisting of a vertically-fluted ball c, mounted on a base c' and supporting a smaller vertically-fluted ball c², which carries a flame-shaped finial c³, and of open-work scrolls and leaf ornaments c⁴, attached to the base and the larger ball.

D represents the body of the stove, the sides, only one of which is completely shown, being alike. It is spheroidal in general outline and comprises two tiers of mica-doors d and d' and arch-shaped mica-frames d² above them. These doors and frames are arranged in two sections or panels, one on each side of the stove between the central vertical column

F and vertically-fluted pilasters d³ at the back and on each side of the stove.

E represents an ornamental jacket between the outer lower edge of the top A and the tops of the arch-shaped mica-frames d² d². It is formed on the sides with fan-shaped ornaments 6 and scrollwork, and has at the back on each side over the pilasters d³ depending volute ornaments 7.

The column F is expanded at its upper end 60 where it joins the jacket E in a leaf-and-scroll ornament 8 and has volute or scroll outline and surface ornamentation its entire length below. The body of the stove is contracted between the upper and lower tiers of doors d 65 and d', which are separated by a half-round vertically-fluted molding 9. The upper tier of doors d are separated from the arched mica-panel frames d² by a plain-faced circular band 10. 70

The doors d and the frames d² constitute in general outline a segment of a sphere, and the doors d' constitute in effect a zone of an intersecting sphere. The frames d² are divided at intervals into quadrangular openings by upwardly-converging stiles or bars and are formed with intersecting scrolls. The door-frames d are divided by horizontal and vertical bars into a row of quadrangular openings at the top and bottom, between 75 which is a row of circular frames separated from each other and joined centrally by horizontal bars. The doors d' are divided by horizontal and vertical bars into two horizontal rows of quadrangular openings. 80 85

G indicates the base of the stove, which has the general form of a truncated quadrangular pyramid rounded vertically at the base and contracted to meet the bottom H, the plain beveled edge of which is exposed to 90 view. The base, which is slightly curved outward near the top, is surmounted by the base-top I, which is in its general form square, corresponding with the shape of the base in cross-section. It is rounded at its 95 corners and rounded or beveled on the front and sides which overhang the base. It is provided on the corners with rosettes or radiate ornaments 11 and on the front between the corners with scroll ornaments. The sides 100

are ornamented with triglyphs 12 or vertical fluting or grooves. The sides of the base G have volute and scrollwork surface ornamentation and to them are secured, by scroll-shaped ornaments *j*, foot-rests J, having rounded ends with volute or scrollwork ornamentation 13. The front of the base, in which is placed the ash-pit door h, has an arch-shaped molding 14 crossing the lower portion of the door and above said molding radiating fluting and cross-line ornamentation. The radiating damper-openings in the door are arranged in the arc of a circle or curve above the arch-shaped molding, and the exposed faces of the damper are provided with basket or woven-work ornamentation. Below the arch-shaped molding 14 is a double scroll-and-leaf ornament 15, below which, in the inward curve of the base, is the clean-out-flue door K. The arrangement of this door K and the ornament 15 and the surface ornamentation is such as to partially hide and obscure said door.

L indicates the base-skirting, which is square in general outline in cross-section,

with rounded corners and vertically-rounded or ovolو-shaped sides. It is provided with volute scroll-and-leaf surface ornamentation, which extends over the upper portion of the legs *ll*, the feet of which are rounded and 30 provided with leaf ornaments 16.

By the arrangement of the mica-doors hereinbefore described in connection with the contour of the body or sides D of the stove an unbroken outline is presented when the 35 stove is viewed from either side, and the fire is fully exposed to view, thereby giving the stove a bright cheerful appearance and pleasing outline and symmetrical form.

I claim—

The design for a heating-stove, as shown and described.

In testimony that I claim the foregoing as my own I affix my signature in presence of two witnesses.

JOHN W. HERRICK.
